FILM DEVELOPING APPARATUS

Ira T. Parker, Tulsa, Okla.

Application June 23, 1937, Serial No. 149,911

15 Claims. (Cl. 95—90)

This invention relates to an apparatus for developing films, and more particularly X-ray dental films, and has for its principal object to provide an apparatus which renders expensive

5 dark room equipment unnecessary.

Other important objects of the invention are to provide an improved light trap in connection with a tank composed of a plurality of sections; to provide a film treating solution inlet and outlet

10 for the device whereby films may be developed, washed and fixed without removing the films from the tank; and to provide improved film holding devices for retaining the films in proper position during the developing, washing and fixing operations.

In accomplishing these and other objects of the present invention, I have provided improved details of structure, the preferred form of apparatus being shown in the accompanying drawings,

20 wherein:

Fig. 1 is a perspective view of a tank embodying the features of the present invention.

Fig. 2 is a vertical cross-section on the line 25

2—2, Fig. 1.

Fig. 3 is a bottom perspective view of the insert section of the tank.

Fig. 4 is a plan view of the tank partly in horizontal cross-section, the top cover being broken away, particularly illustrating the manner of holding the film in position in the tank.

Fig. 5 is an enlarged detail perspective view of one of the clips for holding the film.

Referring more in detail to the drawings:

1 designates a tank which consists of a receptacle preferably of cylindrical shape having a side-wall 2 and a closed end or bottom 3 provided with a stabilizer 4, the receptacle being adapted to be closed by a telescoping cover member 5.

40 The stabilizer 4 consists of an upwardly extending circular boss 6 having a depression 7 centrally located in the upper concaved face thereof, the bottom of the depression being concaved as at 8 for a purpose later described.

45 In order to secure prints that are sharp in detail, it is necessary to exclude all light from the tank during the developing process of the films. The upper periphery of the side-wall 2 is, therefore, provided with a cover seating member

50 9 which also comprises a light trap, said member consisting of a lateral flange 10 spaced slightly downwardly from the upper end of the receptacle 2 and extending outwardly from the side-wall thereof, together with an upwardly directed flange 11 extending slightly above the top edge of

the receptacle in outwardly spaced relation thereto. The flanges form a groove 12 which cooperates with the cover to seal the tank against entrance of light.

In Fig. 3 of the drawings, I have shown the insert section or cover member 5 of the tank which consists of a top member 13 having a depending skirt 14, preferably of cylindrical shape and of a diameter slightly less than the receptacle so that the skirt portion may be received within the side wall 2 of the receptacle. The skirt 14 is spaced inwardly relative to the outer periphery of the insert section. The edge of the cover member is provided with a plurality of downwardly extending spaced flanges 15 and 16, the 15 flange 15 seating in the groove 12 between the top edge of the side-wall 2 and the upwardly extending flange 11 thereof. The flange 16 forms a skirt engaging over the outer surface of the flange 11 for sealing the interior of the tank 20 from light in such a manner that, with the flanges of the top member and receptacle, it is impossible for the light to enter the tank regardless of the closeness of fit of the flanges in the grooves formed thereby.

25 Preferably centrally mounted in the cover member 5 is a funnel 17 consisting of a raised boss 18 having an opening 19, which is restricted as at 20, leading to a pipe 21, the pipe extending to the bottom of the receptacle for engagement 30 with the concaved bottom of the depression 7 for centering the funnel relative to the tank. The pipe 21 is of less diameter than the depression 8 of the stabilizer so that a space 22 is provided therebetween for the passage of film 35 treating fluids through the notches 23 at the lower end of the pipe when fluids are poured into the funnel. Spaced from the bottom of the pipe 21 is a light trap member 24 which consists of a laterally extending flange 25 having a downwardly extending skirt 26 engageable over the boss 6 in such a manner that light passing through the opening 19 in the funnel member or pipe will only reach the concaved bottom 8 at which point it will be stopped by the trap effected 40 by engagement of the member 24 and the boss 6 so that the exterior light will have no harmful effects on films contained in the tank.

45 Mounted on the pipe 21 is a plurality of clips 27, each of which preferably consists of a plate 50 28 having one end secured to the pipe and its other end bent angularly and notched to provide a toothed flange 29. A bracket 30 is provided substantially midway the plate 28 for supporting a plate 31 having a suitable pivotal connection 55

32 relative to the bracket 30. The plate 31 is also provided with an angularly turned notched flange 33 mating with the flange 29 and a finger portion 34. A suitable torsion spring 35 is provided 5 on the pivot 32 in such a manner that the flanges 29 and 33 are normally held together but may be sprung apart by pressure on the finger portion of the plate 31.

The clips 27 are adapted to clip the edge of a 10 series of films 36, the films being of varying sizes depending upon the type of picture taken and the use to which they are to be put. When the 15 films are small, as shown at 37, for example, the clips 27 are of adequate size to securely retain the film in position in the tank. Films of larger size, however, sometimes require additional support and I have provided the grooves 38 which are formed by the space between a series of spaced pairs of parallel ribs 39 suitably formed on the 20 inner surface of the skirt 14. The grooves 38 are preferably spaced in diagonal relation to certain of the clips 27 in such a manner that the larger films may be gripped at one side by the clips and curved, as shown in Fig. 4, for insertion 25 of their other side edges in the grooves 38, the films thus taking less space and consequently requiring less size for the tank 1.

In using my improved developing apparatus, 30 films of various sizes are placed in position to be gripped by the clips and if the films are of large size their opposite ends are engaged in the grooves 38.

A developing solution is poured into the opening 19 of the top for transference into the receptacle through the notches 23 for filling the receptacle 2 to treat the film in the tank, the films being preferably developed at approximately 65° F. for approximately 5 minutes. The developing solution is then poured off through an outlet opening 40 in the edge of the top 13 of the insert tank section. The lower terminus of the opening 40 is located adjacent the groove and the solution passes between the cylindrical walls of the 45 respective tank sections to the opening 40, the upper periphery of the cylindrical wall 2 precluding the entrance of light into the tank.

A suitable washing solution is immediately thereafter poured into the tank through the center opening in a similar manner and subsequently 50 poured off through the outer opening, thereby washing the films free of the developing solution.

A fixing solution is then poured into the central opening 18 in the same manner and is maintained in the tank at approximately 65° F. for a 55 period of time of approximately ten minutes. A stream of running water is then applied to the tank through the central opening thereof for washing the film to remove the fixing solution, the excess water passing out through the opening 40.

It is apparent that the tank need only be tipped to pour any of the solutions therefrom and that the films are engaged by the clips and subsequently placed in the receptacle by merely 65 inserting the section 5 into the receptacle, the flanges at the upper ends of both sections interengaging to provide a light trap and seal at the top thereof and the bottom portion of the pipe 21 interengaging with the stabilizer to provide a 70 light trap at that opening of the tank.

The principal advantages in the apparatus as described are that expensive dark room space or equipment are not required and the apparatus is very simple to handle and clean.

75 Further, the apparatus prevents fogging of

film through leaky light and assures contact of the film with the vital developing solutions at all times.

What I claim and desire to secure by Letters Patent is:

1. In an apparatus of the character described, a tank comprising telescoping sections and having inlet and outlet openings, means in the tank at the inlet and outlet openings for excluding light therefrom, and means in the tank on one 10 of said telescoping sections positioned within the other section when the sections are in telescoped relation for retaining a film in position in the tank for developing treatment.

2. An apparatus of the character described including a tank composed of a plurality of interengagable telescoping sections, means on one of said telescoping sections positioned within the other section when the sections are in telescoped relation for mounting a plurality of films to be 20 treated, means excluding light from the interengaged tank sections, and means for admitting and ejecting solutions to and from the tank for treating the films therein.

3. An apparatus of the character described including a receptacle having interengagable sections, a stabilizer on one of said sections, a top for the receptacle on one of said sections having an inlet member engageable with said stabilizer, an outlet member in one of said sections cooperative with the other of said sections for excluding light from the receptacle, and means for mounting a plurality of films in said receptacle.

4. An apparatus of the character described including a receptacle having interengagable 35 sections, a stabilizer on one of said sections, a top for the receptacle on one of said sections having an inlet member engageable with said stabilizer, an outlet member in one of said sections cooperative with the other of said sections 40 for excluding light from the receptacle, means on one of said sections for mounting edges of a plurality of films, and means on one of the sections for mounting other edges of the 45 films.

5. An apparatus of the character described including a receptacle having a stabilizer, a top for the receptacle having a funnel member engageable with said stabilizer, an outlet in said top cooperative with the receptacle for excluding light therefrom, means on the funnel member for mounting a plurality of films, means on the receptacle for mounting the outer edges of the films, and means on the stabilizer and funnel member for excluding light from the interior 55 of the receptacle.

6. An apparatus of the character described including a tank, a stabilizer in the bottom of the tank, an insert member forming a top for said tank having a skirt engageable in said tank, a funnel member on said insert member engageable with said stabilizer to exclude light from the tank, an outlet in said top offset from said tank to exclude light therefrom, and means for mounting a plurality of films in said tank.

7. An apparatus of the character described including a tank, a stabilizer in the bottom of the tank, an insert member forming a top for said tank having a skirt engageable in said tank, a funnel member on said insert member engageable with said stabilizer to exclude light from the tank, an outlet in said top offset from said tank to exclude light therefrom, and means for mounting a plurality of films in said tank in- 75

cluding clips mounted on the funnel member.

8. An apparatus of the character described including a tank, an insert member forming a top for said tank having a skirt engageable in said tank, the skirt having a groove, and means for mounting a film in said tank including a clip mounted on the insert member in spaced relation to the skirt groove, whereby the film may be engaged by the clip and in the groove.

10 9. An apparatus of the character described including a tank, a stabilizer in the bottom of the tank, an insert member forming a top for said tank having a skirt engageable in said tank, a funnel member on said insert member engageable with said stabilizer to exclude light from the tank, an outlet in said top offset from said tank to exclude light therefrom, means for mounting a plurality of films in said tank including clips mounted on the funnel member, 15 and grooves in the skirt, said grooves being spaced diagonally relative to the clips whereby the films may be curved when mounted therebetween.

10 10. An apparatus of the character described including a receptacle having interengageable sections, a stabilizer on one of said sections for centering said sections, and a top for the receptacle having an inlet member engageable with said stabilizer.

30 11. In an apparatus of the character described, a tank having telescoping sections, means in the tank for excluding light therefrom, means on one of the tank sections for retaining a film in position therein for developing treatment, and an outlet in one of said sec-

tions cooperative with the other of said sections for excluding light from the tank.

12. An apparatus of the character described including a receptacle having interengageable sections, a stabilizer on one of said sections, a top for the receptacle on one of said sections having an inlet member engageable with said stabilizer, means on one of said sections for mounting edges of a plurality of films, and means on one of the sections for mounting other 10 edges of the films.

13. An apparatus of the character described including a receptacle having interengageable sections, means on one of said sections for mounting edges of a plurality of films, and 15 means on one of the sections for mounting other edges of the films.

14. An apparatus of the character described including a tank, a stabilizer in the bottom of the tank, an insert member forming a top for 20 said tank having a skirt engageable in said tank, a funnel member on said insert member engageable with said stabilizer to exclude light from the tank, and means for mounting a plurality of films in said tank including clips mounted on 25 the funnel member.

15. An apparatus of the character described including a tank, a stabilizer in the bottom of the tank, an insert member forming a top for said tank, a funnel member on said insert member engageable with said stabilizer to exclude light from the tank, and means for mounting a plurality of films in said tank including clips mounted on the funnel member.
